UNITED STATES PATENT OFFICE.

JOHN GEORGE ROBINSON AND ROBERT ABSALOM THOM, OF MANCHESTER, ENGLAND,
ASSIGNORS TO THE SUPERHEATER COMPANY, OF NEW YORK, N. Y., A COR-
PORATION OF DELAWARE.

STEAM SUPERHEATER.

Application filed December 27, 1921, Serial No. 524,918, and in Great Britain February 7, 1921.

This invention relates to steam superheaters of the multiple smoke or fire tube type such, for instance, as those usually fitted to locomotive boilers and in which a suitable number of U-loop superheater pipes or elements extend into a number of boiler smoke tubes and have their saturated steam inlet ends and superheated steam outlet ends 5 bent upwardly or laterally and secured to a header situated in the smoke box above or to one side of the group of smoke tubes in which the U-pipes of the superheater elements extend, such header, which may be in the form of a single casting, comprising 10 a saturated steam space or chamber, through which saturated steam from the boiler passes into the elements through the inlet ends thereof, and a superheated steam space or chamber into which superheated steam passes from the outlet ends of the elements and from which latter chamber 15 superheated steam is delivered to the engine cylinder.

In one well known superheater of the type above mentioned, the saturated steam inlet and superheated steam outlet ends of the superheater elements are secured to the header by being expanded directly in holes in the header whereby the most effective 20 steam-tight jointing of the elements to the header is obtained. In this known superheater construction a number of saturated steam chambers or compartments and a number of superheated steam chambers or 25 compartments are arranged side by side and transversely of the header, saturated and superheated steam compartments alternating in the header, and these compartments are closed at the front of the header by removable cover plates which, when removed, give access to the interior of the said steam 30 chambers or compartments for the purpose of expanding the ends of the superheater elements into the bottom or wall of the header and for driving out these ends or disconnecting them from the header when it is required to remove an element or elements from the boiler smoke tubes, all of the saturated steam chambers being in communication with a channel or space in the 35

header which receives saturated steam from the boiler and all of the superheated steam chambers being in communication with a channel or space in the header which receives superheated steam from the said 55 chambers and from which the superheated steam is conveyed by the usual steam pipes to the engine valve chests.

The present invention has for its principal objects to provide a superheater in 60 which, while the ends of the superheater elements are joined to the header by being expanded directly in holes in the header wall, the form or construction of the header is not only simple but is further such as to 65 give greater facility for expanding the ends of the superheater elements into and for driving out or extracting these ends from the header, the construction and arrangements being further such that these expanding and 70 extracting operations can be readily performed by means of ordinary tools such as those usually employed for expanding in and extracting boiler tubes. Further the form or construction of the header is such 75 that the cross area of the steam spaces or chambers of the header can be made as small as practicable with a consequent reduction in weight and bulk of the header which can therefore be readily fitted to 80 drum-head boilers.

Further the invention consists in a steam superheater comprising a header and steam superheater elements substantially as hereinafter described with reference to and illustrated by the accompanying drawings in 85 which,—

Figs. 1 and 1^a together constitute a front view of the upper portion of the smoke box end of a locomotive boiler with the 90 front or door removed and show a superheater according to this invention, the portion of the header in Fig. 1^a being in sectional elevation, the section being taken on the line 1^a—1^a of Fig. 3.

Fig. 2 is a plan of the portion of the header shown in Fig. 1.

Fig. 2^a is a sectional plan of the portion of the header shown in Fig. 1^a, the section being taken on line 2^a—2^a, Fig. 3.

Fig. 3 is a side view partially in section, of part of a locomotive boiler showing the superheater illustrated in Figs. 1 and 1^a.

Fig. 4 is a detail view drawn to a larger scale showing portions of two adjacent depending steam chambers or pockets of the header and also showing one of the superheater elements with its end portions moved to the position in which they lie one behind the other to enable them to be drawn forwardly through the space or opening between the steam pockets.

Fig. 5 is a transverse section of the header taken on the line 5—5 Fig. 1^a.

15 In the following description of a superheater according to this invention as illustrated in the accompanying drawings, like reference numbers indicate corresponding parts in the several figures of the drawings.

20 Referring to the drawings 1 indicates a portion of the barrel of a locomotive boiler, 2 the smokebox wall or shell, 3 the boiler tube plate at the smoke box end of the boiler and 4 the usual enlarged smoketubes 25 of the boiler into which the U-pipes of the superheater elements extend as usual.

25 5 is the superheater header which as shown is a casting (it may be an iron or a steel casting as desired) in which are formed two longitudinal steam chambers or channels 6 and 7 arranged one behind the other and extending from end to end of the header, the chamber 6 being a saturated steam chamber which receives saturated steam from the rearwardly extending tubular part 8 formed integrally with the header and provided with a flange 9 whereby the said tubular part 8 is secured to the boiler tube plate 3 in registration with the aperture 10 therein in which the outlet end of the usual saturated steam pipe of the boiler is fitted, the flange 9 being secured to the tube plate 3 in any suitable manner for instance by means of bolts or studs and nuts as usual. 11 and 12 (see Figs. 1 and 1^a) are, respectively, the hereinbefore mentioned downwardly projecting or depending saturated and superheated steam chambers or pockets the saturated steam chambers 11 being in communication at their upper ends with the longitudinal saturated steam chamber or channel 6 as clearly shown in Fig. 3, and the superheated steam chambers or pockets 12 being in communication at their upper ends with the longitudinal superheated steam chamber or channel 7 as clearly shown in Figs. 1^a and 5, the communication between the depending saturated steam chambers or pockets 11 and the saturated steam chamber 6 being 60 through the rearwardly sloping passages 11^a forming extensions of the said pockets 11. 13 are the hereinbefore mentioned relatively narrow openings formed in the header casting between adjacent depending steam pockets or chambers 11 and 12. As clearly

shown in Fig. 1^a, the saturated steam inlet ends 14 of each of the superheater elements appertaining to the boiler smoke tubes in two adjacent vertical rows of these tubes are expanded in holes 15 in the rear wall of one of the depending saturated steam chambers or pockets 11, the superheated steam outlet ends 16 of the elements appertaining to one of the said vertical rows of smoke tubes being similarly expanded in holes 17 in the rear wall of the depending superheated steam pocket or chamber 12 situated to one side of the pocket 11 while the superheated steam outlet ends 16 of the elements appertaining to the other vertical row of smoke

70 tubes are similarly expanded in holes in the rear wall of the depending superheated steam pocket or chamber 12 situated to one side of the pocket 11, the arrangement being such, as clearly shown in Fig. 1^a,

75 that each depending saturated steam pocket or chamber 11 has the saturated steam inlet ends of all the elements appertaining to two adjacent vertical rows of the boiler smoke tubes secured in its rear wall by being ex- 80

panded in holes therein and each depending superheated steam chamber or pocket 12 has the superheated steam outlet ends of all of the elements appertaining to two adjacent vertical rows of the boiler smoke tubes se- 85

90 cured to its rear wall by being expanded in holes therein, with the exception, in the ex- 95

ample shown, of the saturated steam chambers or pockets 11 at the ends of the header in which, as shown in Figs. 1 and 1^a, the 100

95 saturated steam inlet ends of the super- 105

heater elements appertaining to only one vertical row of the boiler smoke tubes are 110

expanded in the respective chambers 11 at opposite ends of the header. 18 are the 115

105 U-loop superheater elements, the U-pipes of an element as usual extending into one of the boiler smoke tubes 4. As clearly shown in Fig. 3 the end portions of the super- 120

110 heater elements 18 which extend from the boiler smoke tubes 4 to the rear walls of the depending steam chambers 11 and 12 of the header are bent upwardly and forwardly 115

115 and are further so bent or set that one of the said portions—in the example shown the superheated steam outlet portion marked 18^a Fig. 3—is situated in advance of the other or 120

115 saturated steam inlet portion marked 18^b Fig. 3, the construction and arrangement being such that when the ends of an element 125

120 are disconnected from the rear wall of adjacent steam chambers or pockets 11 and 12 the portions 18^a, 18^b of the element can be 125

120 pressed or moved towards each other so that the portion 18^a of the element will lie be- 130

125 hind the portion 18^b in the same plane and in alignment with the opening 13 between the adjacent steam chambers or pockets 11 and 12 as clearly shown in Fig. 4 whereupon 130

125 the element can be drawn forwardly out of 130

- the boiler smoke tube. Similarly for inserting an element in the boiler smoke tube the ends 18^a, 18^b of the element will be moved to and held in position one behind the other, 5 as shown in Fig. 4, so that these portions 18^a, 18^b will, in moving the element into the boiler smoke tube, pass through the space 13 between the adjacent steam chambers 11 and 12, and when the extreme ends (inlet 10 and outlet ends respectively 14 and 16) of the said portions 18^a, 18^b of the element have passed through the opening 13 clear of the rear walls of the chambers 11 and 12 the said portions 18^a, 18^b of the element will 15 spring apart so that they can be readily inserted in the holes 15 and 17 in the rear walls of the said chambers 11 and 12 for the purpose of being expanded in the said holes.
- 20 Fig. 4 shows the position or approximately the position assumed by the longitudinal pipes of the element, (which form extensions of the portions 18^a, 18^b and extend into the smoke tube 4) when the said portions 18^a, 18^b are moved to and held in the position one behind the other as shown in Fig. 4. The horizontal front end portions of the lower stretches of the pipes 18 are sprung in opposite directions so that 25 they lie one above the other, as indicated by the numerals 18^c and 18^d in Fig. 4, and the inclined end portions 18^a and 18^b of the pipes are in the same vertical plane.
- 30 19 indicates the openings in the front of each of the depending steam pockets or chambers 11 and 12 19^a being the flange surrounding the said opening and 20, Figs. 1 and 3, are the hereinbefore mentioned cover plates or hand hole doors which are 35 fitted to each of the depending chambers 11 and 12 respectively for closing the front of same in a steam tight manner; as shown in Fig. 3 a projecting portion of the inner side of the cover 20 enters the opening 19 in the chamber 11 and the face of the cover 40 surrounding the said projecting portion bears on the outer face of the flange 19^a the said faces being machined so as to enable an effective steam tight joint to be made.
- 45 50 Each of the hand hole doors or cover plates 20, in the example shown, is secured to the respective steam chambers or pockets 11 and 12 by means of a T-bolt 21 the T-head of the bolt, when in position securing the door or cover 20 to the header, extending transversely of the opening 19 in the respective depending steam chamber and engaging behind the vertical portion of the flange 19^a surrounding the said opening 22 55 being a nut which when screwed up on the outer end of the bolt 21 which projects from the outer side of the cover 20, securely clamps the cover in position on the header.
- 60 As clearly shown in Figs. 1 and 1^a the 65 short depending steam chambers 11 and 12
- terminate at their lower ends at a position above and thus clear of the enlarged smoke tubes 4 in the uppermost horizontal row of such tubes; consequently the smoke tubes in the uppermost horizontal row, as well as 70 those in the lower horizontal rows, can be removed from the boiler by being drawn forwardly through the smoke box, without having to remove the header from its fixed position in the smoke box. It is also clearly 75 shown, by Figs. 1 and 3, that on removal of the cover plates or doors 20 from the front of the depending steam chambers or pockets 11, 12 the ends of the superheater elements in the holes in the rear walls of 80 these chambers are immediately accessible for the purpose of either expanding these ends in or disconnecting them from the said steam chambers, and that the operations for expanding the ends of the elements in the rear walls of the chambers 11 and 12 and the operations for disconnecting these ends from the said walls can be conveniently 85 performed by means of the ordinary tube expanding and extracting tools usually employed for expanding and extracting the tubes of boilers.
- 90 What we claim as our invention and desire to secure by Letters Patent is:—
- 95 1. A steam superheater header for a locomotive boiler, comprising two chambers for saturated steam and for superheated steam respectively arranged one in front of the other and each provided with a series of branch chambers depending from them and arranged alternately, said chambers and branch chambers being of a total height for installation in the boiler smoke box wholly above the level of its fire-tubes so as to permit the removal of said fire-tubes, the said branch chambers each having holes in their rear sides for the expanded end portions of superheater pipes, said holes being arranged horizontally in pairs, one pair above another, and said branch chambers having spaces between them of such narrow width as only to permit the end portions of the superheater pipes to be slid through them when said end portions are sprung into the same vertical plane.
- 100 105 110 115 120 125
2. A superheater header as set forth in claim 1, in combination with superheater tubes each having its two end portions inclined upwardly and forwardly with one end portion arranged partially in advance of its other end portion.
3. In a superheater header for locomotives, a saturated steam chamber, a superheated steam chamber located adjacent to and in front of the saturated steam chamber, branch superheated and saturated steam chambers depending from the superheated steam chamber and connected to the two steam chambers alternately, said branch chambers being arranged wholly above the

top row of boiler smoke-flues and permitting the removal of said flues without disconnecting the superheater from the boiler, the said branch chambers each having two ⁵ series of holes for receiving superheater tubes when arranged side by side, and said branch chambers having spaces between them of less width than the width of the

branch chambers and adapted for the passage of superheater tubes only when said ¹⁰ tubes are arranged one above another.

In testimony whereof we have affixed our signatures.

JOHN GEORGE ROBINSON.
ROBERT ABSALOM THOM.
